UNITED STATES PATENT OFFICE

HENRY L. AUSTWICK, OF CHICAGO, ILLINOIS.

GAS-HEATER AND CHAFING-DISH HOLDER.

1,002,957.

Specification of Letters Patent. Patented Sept. 12, 1911.

Application filed December 2, 1910. Serial No. 595,278.

To all whom it may concern:

Be it known that I, HENRY L. AUSTWICK, a citizen of the United States, residing at Chicago, in the county of Cook and State 5 of Illinois, have invented certain new and useful Improvements in Gas-Heaters and Chafing-Dish Holders, of which the following is a specification.

My present invention relates particularly 10 to a portable device for adjustment upon a gas burner, and embodying a holder and a heater in the form of a hood removably held in engagement with the holder, the said holder being adapted to receive and retain 15 a chafing dish or other vessel in which articles of food may be heated or cooked, when the heating element or member is removed. With this in mind my improved invention resides in the features of construction and arrangement to be hereinafter described with reference to the accompanying drawing forming a part of this specification, and in which,

Figure 1 is a central vertical sectional 25 view through my improved device, showing the same in operative engagement upon a gas burner, with the heater in position.

Fig. 2 is a fragmentary elevation illustrating the connection of one of the free ends 30 of the supporting frame, and Fig. 3 is a bottom plan view of the central portion of the heating hood.

Referring particularly to these figures, the supporting frame of my improved device 35 comprises a single wire which is bent double at its central portion, and the doubled sections coiled for some distance to form a socket 5 adapted to fit about a gas burner 6 as shown in Fig. 1. The extensions 7 and 8 of said wire are then bent, as shown, upwardly and divergently from the socket 5, to a selected height, at which points they are bent angularly toward one another and then upwardly to provide small 40 offsets 9. From these points the extensions 7 and 8 of the wire are bent toward one another in semi-circles indicated at 10, and their extremities 11 are bent outwardly and downwardly and coiled securely about the 45 offset 9 of the opposite extension. In this manner I form a frame which is rigid and

strong, and embodies an upper circular portion in which a chafing dish or other vessel (not shown) for heating or cooking food, may be disposed and held over the burner 6. 55

The heating member, which is used for heating the air within, and warming, a room, comprises a substantially concavo-convex hood 12 which, when disposed upon the holder just described, rests upon the 60 upper circular frame of said holder, and which has a depending circular flange 13 at its edge which extends downwardly upon the outside of the wire extensions 7 and 8 below their offsets 9. This hood 12 has a 65 central depending thimble 14 provided with a reduced end 15 on which is disposed a circular fire-brick 16, this fire-brick being held in position by means of a cotter-pin or the like 17, projecting through the reduced portion of the thimble below the said fire-brick. This fire-brick is thus held in 70 position above the burner 6 to receive the direct rays of the flame therefrom, and its function is to prevent the hood 12, which 75 is of metal, from becoming burned out, and also to radiate the heat through the surrounding air.

From the foregoing it will be readily seen that I provide a device which may be 80 conveniently used either as an air heater, or as a support for a cooking vessel, without impairing the light in a room, and which is portable, and may be easily inserted in, and removed from, its operative 85 position.

I claim:

1. The combination of a frame comprising a lower burner engaging portion and an upper, circular dish supporting portion, 90 a removable heating hood adapted to rest upon said circular portion and having a surrounding flange to hold the same in position, and a heat distributing member carried by, and removable with, said hood. 95

2. The combination of a supporting frame comprising a wire doubled at its central point to form extensions and having its double portion coiled to form a socket adapted to fit over, and support the frame 100 upon a gas burner, each of the extensions of said wire being bent upwardly and

formed with an offset, and being bent beyond said offset, into a semi-circular portion having its extemity bent at an angle and coiled about the offset of the opposite 5 extension, and an air heating hood embodying a flange to surround the said semi-circular portions of said frame.

In testimony whereof I affix my signature in presence of two witnesses.

HENRY L. AUSTWICK.
